E. E. PARSLOW.
VALVE STEM LUBRICATOR.
APPLICATION FILED MAY 6, 1921.

Patented July 4, 1922.

FIG. 1

FIG. 2

INVENTOR.
EARL E. PARSLOW
A. B. Bowman
ATTORNEY

UNITED STATES PATENT OFFICE.

EARL E. PARSLAW, OF SAN DIEGO, CALIFORNIA.

VALVE-STEM LUBRICATOR.

1,421,826.

Specification of Letters Patent.

Patented July 4, 1922.

Application filed May 6, 1921. Serial No. 467,412.

To all whom it may concern:

Be it known that EARL E. PARSLAW is a citizen of the United States, residing at San Diego, in the county of San Diego and State 5 of California, has invented a certain new and useful Valve-Stem Lubricator, of which the following is a specification.

My invention relates to a device for lubricating valve stems particularly the intake 10 and exhaust valves for gas engines, and the objects of my invention are: First, to provide a device which will automatically lubricate the valve stems of gas engines; second, to provide a device of this class, which 15 is applicable for use in connection with several makes of vehicles now in use; third, to provide a device of this class which communicates with the interior of the crank case for conducting air, laden with oil from the 20 interior of the crank case against the valve stems in a position for efficiently lubricating the valve stems; and fourth, to provide a device of this class, which is very simple and economical of construction, durable, easy to 25 install, automatic in its action and which will not readily deteriorate or get out of order.

With these and other objects in view, as 30 will appear hereinafter, my invention consists of certain novel features of construction, combination and arrangement of parts and portions, as will be hereinafter described in detail and particularly set forth in the 35 appended claims, reference being had to the accompanying drawings, and to the characters of reference thereon, which form a part of this application in which:

Figure 1, is a sectional view of a fragmentary portion of the conventional gas engine 40 crank case and valve supports, showing the valves in elevation to facilitate the illustration and showing my lubricating device in elevation in operative position in connection therewith. Fig. 2, is a fragmentary side 45 elevational view of the upper end of the lubricating device at a right angle to that of Fig. 1.

It will be noted that applicant has disclosed his device in connection with a dodge 50 engine intake and exhaust valve construction, but it is obvious that the same construction may be used in connection with other engines of similar make of valve and valve operating structures.

55 My invention consists of a hollow lug bolt

1, provided with apertures 1^a in opposite sides thereof communicating with the interior of said bolt. This bolt is threaded at its lower end and is positioned in a tapped hole in the crank case and positioned intermediate the intake and exhaust valve operating mechanism and positioned so that the apertures 1^a face the valve stems on opposite sides, and is of sufficient length so that the apertures are directly opposite the valve 60 stems adjacent the valve stems support, so that air laden with lubricating oil is forced from the crank case through the hollow bolt and out through the apertures 1^a against the valve stems, automatically lubricating 65 the same with the operation of the engine, which is generally termed the breathing of the crank case.

In the installation disclosed herein the bolt 1 is substituted in the place of the ordinary lug bolt in a thread hole in the crank case and in this construction performs the double function of lubricating the valve stems and also serving as a lug bolt for supporting the lugs 2, so that it supports the 70 valve operating plunger support by means of a nut 4.

It is obvious however, that in case there is no lug bolt, a hole may be made in the crank case and tapped and the bolts inserted therein as shown and if desired the nut 4 may be used as a lock nut for preventing the hollow bolt 1 from turning.

Though I have shown and described a particular construction, combination and arrangement of parts and portions, I do not wish to be limited to this particular construction, combination and arrangement, but desire to include in the purview of my invention, the construction, combination and arrangement substantially as set forth in the appended claims.

It is obvious that with this construction, there is provided a means for lubricating the valve stems of gas engine by conducting 100 lubricating oil saturated air from the crank case of the engine through the conductor and out through apertures in said conductor to a position where it most efficiently lubricates the valve stems; that the place of lubrication, may be readily regulated by the length of the hollow bolt or the depth said bolt is mounted in the crank case; that it does not only lubricate the valve stems, but it automatically lubricates the operating 105 110

plungers and provides support for the valve operating mechanism.

Having thus described my invention, what I claim as new and desire to secure by Letters Patent is:

1. A device of the class described, including the combination with a poppet valve stem of a gas engine valve, of a conducting tube communicating with the interior of the 10 crank case at one end and its other end provided with an aperture contiguous to the gas engine valve stem.

2. A device of the class described including, the combination with the intake and exhaust valve of a gas engine of a conductor interposed between said valve stems and one 15 end communicating with the interior of the crank case, its other end provided with

oppositely disposed apertures facing toward said valve stems.

3. A device of the class described, including the combination with the intake and exhaust valves of a gas engine of a conductor interposed between said valve stems and its one end communicating with the interior of 25 the crank case, its other end provided with oppositely disposed apertures facing toward said valve stem, comprising a hollow bolt threaded at one end, screwed in a threaded hole in the crank case and its extended end 30 provided with apertures communicating with the interior of said bolt.

In testimony whereof, I have hereunto set my hand at San Diego, California, this 29th day of April 1921.

EARL E. PARSLOW.
